ELECTRIC HAIR COMB AND HAIR STRAIGHTENING MEANS

Harry G. Anderson, New York, N. Y.

Application February 18, 1932. Serial No. 593,708

5 Claims. (Cl. 219—21)

This invention relates to new and useful improvements in electrically heated combs used for straightening curly hair.

It is a well known human weakness that those who have straight hair often like to have their hair artificially curled, while those who have naturally wavy hair are sometime desirous of having their hair straight. To satisfy the desire of the latter class there are available electrically heated combs for straightening curly hair.

The combs of this type now available are made of some metal to resist heat, and provision is made to heat them electrically by means of a heating element housed in the hollow upper part of the comb.

When using this appliance, small portions of the hair are first smoothened out by means of the teeth of the comb, and when the hair is in the desired condition of smoothness heat is applied to it in order to fix and make lasting the smoothness previously obtained.

Such use of the present devices is not without inconvenience to the user, since the teeth of the comb form one body with the part containing the heating element, due to which the teeth attain approximately the same temperature as the hollow part containing the heating element. Accordingly, there is danger of burning the scalp with the hot teeth of the comb, and the user cannot properly smoothen the hair before applying the heat.

My present invention obviates the difficulty described in the foregoing by thermally insulating the part containing the heating element from the teeth of the comb. With this arrangement the upper part of the comb may attain a high temperature without appreciably heating up the teeth, and thus the user may effectively smoothen the hair with the teeth of the comb before applying the heat for securing an approximate permanency of the condition of the hair thus arranged or straightened out.

Another advantage of the arrangement disclosed in this invention is that the comb proper is easily detachable from the rest of the appliance, thereby facilitating sterilization of the said comb. This is a particularly desirable feature in barber shops or beauty parlors where the same device may be used by a large number of customers.

With the above and other objects in view, this invention consists of the novel features of construction, combination and arrangement of parts, hereinafter fully described, claimed, and illustrated in the accompanying drawing forming

part of this specification, and in which similar characters of reference indicate corresponding parts in all views, and in which:

Fig. 1 is a perspective view of the device, looking from the front.

Fig. 2 is a perspective view of a metallic spacer which may be used in conjunction with the device.

Fig. 3 is an enlarged cross-section taken along line 3—3 in Fig. 1, and

Fig. 4 is a cross sectional view similar to Fig. 3, but showing a modified arrangement.

In the accompanying illustrations 11 is a hollow housing, and inside this housing, electrically insulated therefrom, there is arranged a heating element 12. The said heating element 12 is connected to a source of current by means of a cord 13, and the flow of current can be controlled by means of a tumble switch 14 housed in the handle 15 of the device. The said handle 15 is hollowed out for the purpose of concealing therein part of the cord 13.

A collar 16 is fastened to the handle 15, the said collar being formed with a protruding, substantially square part 17. The comb proper bears the numeral 18, and it is supported by an offset stem 19. The end of the said stem is inserted into the square part 17 of the collar 16, and the connection between the stem and the handle is completed by means of the machine screw 20 which is threadedly connected to the collar 16. With this arrangement the comb part can be easily detached or attached to the handle for sterilization.

There is an air space 21 between the housing containing the heating element and the comb, due to which any heat transmission between the heating element and the comb proper has to take place by radiation and not by convection as is the case with devices where the heating element is housed in the upper part of the comb proper.

With this arrangement there will be a considerable difference between the temperature of the housing 11 and the comb proper, thereby greatly increasing the usefulness of the appliance, and at the same time eliminating the danger of burning the user's scalp.

At the time when the appliance is being put into use it may be desirable to heat up rapidly the comb proper to a moderate temperature. To achieve this end a metallic spacer 22 shown in Fig. 2 may be inserted into the space 21, the dimensions of the said spacer being such as to fit snugly between the housing 11 and the comb proper. For convenience in handling there is a lug 23 arranged upon the spacer 22.

The arrangement shown in Fig. 4 carries the

idea of protecting the user's scalp one step further. This figure shows a cross section of the device, similar to that illustrated in Fig. 3, with the difference, however, that the section is taken through a space between two teeth of the comb.

5 The important feature of this modification is that the teeth 24 of the comb have an upwardly projecting portion 25 which prevents the right hand surface of the housing 11 coming into contact with the scalp. The purpose of this added protection is to shield the scalp when the comb is laid upon the head with the concave side up as preferred by some users.

10 It is obvious that changes may be made in the form, construction and arrangement of the several parts, as shown, within the scope of the appended claims, without departing from the spirit of the invention, and I do not, therefore, wish to limit myself to the construction and arrangement shown and described herein.

15 What I claim as new, and desire to secure by Letters Patent of the United States, is:

20 1. A device for straightening hair, comprising a housing containing an electric heating element and being fastened to a handle, a comb attached to the latter by means of a shank, and being thermally insulated from the said housing, the teeth of the comb having an upwardly extending portion shielding the rear of the said housing.

25 2. A device for straightening hair, comprising a housing containing an electric heating element and being fastened to a handle, a comb attached

30 to the latter by means of a shank, and being thermally insulated from the said housing, a spacer adapted for insertion between the said housing and the comb proper, the said spacer being provided with a lug, whereby to adjust the latter.

35 3. A device for straightening hair, comprising a housing containing an electric heating element and being fastened to a handle, a comb attached to the latter by means of a shank, and being thermally insulated from the said housing, the back of the housing being provided with a large convex surface, whereby to impart impressions upon the hair.

40 4. In a device for straightening hair, the combination of an electric heating element, contained in a housing, with a comb arranged in spaced relation to the latter, the said comb having an elongated handle attached to the said housing, and a spacer formed with a concave upper surface and adapted for insertion between the said housing and comb proper.

45 5. A device for straightening hair, comprising a housing containing an electric heating element and being fastened to a handle, a comb attached to the latter by means of a shank, and being thermally insulated from the said housing, the back of the housing being provided with a large exposed surface for imparting heat to the hair during treatment of the latter.
